UNITED STATES PATENT OFFICE.

ARTHUR W. COX, OF BALLARD VALE, MASSACHUSETTS.

DESIGN FOR A KNIFE-HANDLE.

SPECIFICATION forming part of Design No. 16,785, dated July 13, 1886.

Application filed May 22, 1886. Serial No. 363,649. Term of patent 14 years.

To all whom it may concern:

Be it known that I, ARTHUR W. COX, a citizen of the United States, residing at Ballard Vale, in the county of Essex and State of Massachusetts, have invented and produced a new and original Design for Knife-Handles; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

Figure 1 is a plan view of my newly-designed knife. Fig. 2 is an edge view.

The leading feature of my design consists in a handle for table-cutlery having an enlarged or expanded end or butt comparatively with the blade-receiving end, which end is reduced and rapidly expanded laterally on each side of the blade at or near its junction therewith, forming an extended surface on the top and bottom of the handle at right angles to the plane of the blade. The blade A is double-

edged, and the handle B, projecting therefrom about midway between the edges, is expanded laterally on each side of the plane of the blade, forming an extended surface, b^3 , on the top and bottom of the handle at the reduced or 30 blade-receiving end. The handle gradually enlarges as it recedes from the blade end and nears the butt, forming the enlarged end b^2 and the intermediate narrow portion, b' , as clearly shown in Fig. 1. 35

I claim—

The design for a knife-handle or kindred article of table-cutlery herein shown and described, the same consisting of the enlarged butt and the reduced end, expanded laterally 40 on each side of the blade, forming an extended surface, b^3 , on the top and bottom of the handle, at right angles to the plane of the blade, at or near the junction therewith.

In testimony whereof I affix my signature in 45 presence of two witnesses.

ARTHUR W. COX.
